UNITED STATES PATENT OFFICE.

JACOB GOGEL, OF TOLEDO, OHIO.

OIL-BURNER.

No. 880,971.

Specification of Letters Patent.

Patented Feb. 26, 1908.

Application filed April 26, 1906. Serial No. 313,544.

To all whom it may concern:

Be it known that I, JACOB GOGEL, a citizen of the United States, and a resident of Toledo, in the county of Lucas and State of Ohio, 5 have invented certain new and useful Improvements in Oil-Burners; and I do hereby declare the following to be a full, clear, and exact description of the invention, such as will enable others skilled in the art to which 10 it appertains to make and use the same, reference being had to the accompanying drawings, and to the figures of reference marked thereon, which form a part of this specification.

15 My invention relates to burners of the force-blast type for the purpose of heating furnaces, brazing, or the like and in which hydro-carbon oils of low gravity, such, for example, as kerosene or crude petroleum, are 20 employed as a fuel.

The object of my invention is the provision of a simplified and improved burner of this class, by means of which a purer oil-gas and a more perfect combustion is effected than is 25 possible with burners of the kind now in use.

Further objects of my invention together with the operation, construction and arrangement of the parts thereof will be apparent by reference to the following description and to 30 the accompanying drawings illustrating one form thereof, in which,—

Figure 1 is a longitudinal central vertical section of the burner embodying my invention, Fig. 2 a top plan view thereof, Fig. 3 an 35 elevation of one of the spreader-gates, and Fig. 4 a rear elevation of the baffle-plate against which the hydrocarbon stream first 40 impinges on its discharge from its jet.

Referring to the drawings, 1 represents the 45 combustion-chamber of the burner into which the liquid hydrocarbons and air from a suitable air-blast are mixed and converted into a highly inflammable material, which, when ignited, creates an intense heat, such as is 50 adapted for brazing, welding, or the like. This chamber is provided at its rear with an upwardly extending neck 2, which communicates with a pipe 3 leading to any suitable air-blast, and has its forward end terminating in 55 the slightly contracted nozzle 4, through which the flame-blast is emitted. This nozzle has its discharge at an angle to the major axis of the burner, as it is found that a more efficient burner is thereby provided than

would be the case were the discharge straight 55 from the end of the burner.

Tapped into the rear end of the chamber 1 in substantial longitudinal alignment with its major axis is a jet 5 for the discharge of oil therein, said jet being in communication with 60 a supply-pipe 6 and having its discharge controlled by the needle-valve 7. To enable the jet 5 and its valve to be positioned in this manner the pipe 3 leading to the air-blast is slightly offset, as shown, so as to escape said 65 parts in its downward course.

8 represents a rod or bar, which is disposed centrally within the shell forming the combustion-chamber and has its forward end threaded or otherwise suitably secured thereto, as at 9, and its rear end extending to adjacent the mouth of the neck 2. To the inner or rear end of this rod or bar is threaded or otherwise suitably secured a baffle-plate 10, which has a conical projection 11 formed on 70 its rear face with its point in the direct line of discharge of the jet 5, thus causing the stream of oil emitted from said jet to strike against said projection and plate and be broken up 75 and radiated laterally in spray form thereby. 75 This plate has its lower portion preferably extended downwardly in contact with the floor of the shell to enable it to act as a supporting leg for the inner end of the rod or bar 8, and has its lower edge notched or cutaway, as 80 shown at 12, to permit the oil which falls to the floor and also a portion of the air-blast or current to pass thereunder, thus preventing 85 an accumulation of the oil on the floor of the combustion-chamber. 90

Mounted axially on the rod or bar 8 intermediate its ends are the two spreader-gates 13 and 14, the former of which is disposed within the combustion-chamber in advance of the baffle-plate 10, while the latter is disposed within or adjacent the entrance to the contracted discharge nozzle 4 of the burner-shell, as shown in Fig. 1. These gates are substantially of the shape and size of the internal cross-sectional area of the shell of the 100 burner at the points therein where it is desired to position them, and each consists of a plurality of spaced parallel bars 15, carried by a cross-bar 16, as shown in Fig. 3. In order to facilitate the proper relative adjustment of the gates 13 and 14 within the burner they are threaded on the rod or bar 8 from 105 one end thereof. It is found by positioning

these gates so that the bars of one are disposed at right-angles to those of the other that the oil is more efficiently spread or broken up, thereby producing a pure oil-gas.

5 The top of the combustion-chamber is provided with an opening 17, which is normally closed by a heavy metal lid 18, which is hinged to the shell, as at 19, and is of sufficient weight to prevent its being lifted by the 10 force of the blast.

20 20 represent legs or standards, which are secured to lugs or flanges 21, 21 on the under side of the burner-shell and act as supports therefor.

15 The operation of the invention is as follows:—When it is desired to start the burner, an oil saturated wick or roll of cotton, wadding or the like is passed through the opening 17 in the shell and placed in the bottom of the 20 combustion-chamber 1 and lighted. The valve in the jet 5 is then opened and the liquid hydrocarbons emitted therefrom are discharged against the conical projection 11 and baffle-plate 10 by which it is caused to spread 25 or radiate laterally in spray form. This spray is caught by the air-blast which enters the combustion-chamber through the neck 2 and pipe 3 and with which it mixes and is forcefully carried by it through and over the 30 flame arising from the burning material in said chamber by which it is ignited. As the blast is forced through the spreader-gates 13 and 14 the air and hydrocarbons are caused to spread or be broken up, thereby forming a 35 purer gas than would be possible without such gates, and the free passage of the flame-blast from the burner is also obstructed and baffled so as to cause the igniting flame to more thoroughly act on the gases. It is 40 found that the burner will not work when these gates are both eliminated from its construction and that the operation is not entirely satisfactory when only one gate is employed.

45 I wish it to be understood that I do not desire to be limited to the exact details of construction shown and described, for obvious modifications will occur to a person skilled in the art.

50 Having thus described my invention, what I claim as new, and desire to secure by Letters Patent, is, —

1. The combination with the combustion-chamber of an oil-burner, of a plurality of 55 spreader-gates through which the products of combustion pass, said gates being axially arranged therein and adjustable toward and away from each other.

2. The combination with the combustion-chamber of an oil-burner, and the jet tapping one end thereof, of a baffle-member and a spreader-gate disposed in opposite portions of the chamber and being relatively adjustable.

65 3. The combination with the combustion-

chamber of an oil-burner, of a plurality of spreader-gates mounted within the chambers adjacent the discharge end thereof, and an element adjustably carrying said gates.

4. The combination with the combustion-chamber of an oil-burner, of a baffle-member and a plurality of spreader-gates, and a common member carrying all of said parts, the spreader-gates being adjustable relative to the baffle-member and to each other. 70

5. An oil-burner, comprising, in combination, a shell having one end angled and contracted to form a discharge nozzle, its other end contracted and forming an air inlet, and its central portion forming a combustion-chamber and provided with a stoppered opening, a jet tapped into the air-inlet end of the shell, and a baffle member and spreader means disposed intermediate the shell ends, said member and means being relatively ad- 80 justable. 85

6. An oil-burner, comprising a shell forming a mixing-chamber and a combustion-chamber and having an opening over the combustion-chamber and its ends angled and one forming an air-blast intake and the other a discharge nozzle, a lid for the opening, an oil-jet tapped into the intake end of the shell, a rod carried by and projecting within the shell, a baffle-plate carried by the rod in the 90 line of discharge of the oil-jet, and a plurality of spreader means carried by the rod intermediate the baffle-plate and the end of the discharge nozzle. 95

7. A burner having a discharge nozzle and a crooked air-blast intake at opposite ends, a jet at the intake end for the discharge of hydrocarbon liquids to the burner, a baffle-plate having a conical projection in the path of discharge of the jet, and a spreader-gate 100 between the baffle-plate and nozzle. 105

8. A burner having a discharge nozzle, an air intake, a jet tapped into its intake end, and a combustion-chamber intermediate the nozzle and intake ends, in combination with 110 a baffle-plate and a plurality of spreader-gates disposed between the jet and nozzle, each of said gates being relatively adjustable and formed of parallel bars disposed at an angle to the bars of the other gate. 115

9. A burner comprising an oblong shell having its ends angled and one forming a discharge nozzle and the other communicating with an air-blast, a rod or bar disposed longitudinally within the shell, a baffle-plate carried by the rod adjacent the air-intake, a plurality of spreader-gates carried by the rod in advance of the baffle-plate, and a jet disposed to discharge a hydrocarbon liquid against the rear face of the baffle-plate, substantially as described. 120 125

10. An oil-burner comprising a shell forming a mixing-chamber and a combustion-chamber intermediate its ends and having its ends angled and one forming an air-blast in- 130

one and the other a discharge nozzle, an oil-jet tapped into the intake end of the shell, a baffle-plate in the line of discharge of the oil-jet and one or more spreader-gates between the point of position of the igniting agent in the combustion-chamber and the end of the discharge nozzle.

In testimony whereof I have hereunto signed my name to this specification in the presence of two subscribing witnesses.

JACOB GOGEL.
